UNITED STATES PATENT OFFICE.

WILLIAM H. HANKIN, JR., OF OTISVILLE, NEW YORK.

BUCK-SAW FRAME.

SPECIFICATION forming part of Letters Patent No. 225,928, dated March 30, 1880.

Application filed February 17, 1880.

To all whom it may concern:

Be it known that I, WILLIAM H. HANKIN, Jr., of Otisville, in the county of Orange and State of New York, have invented certain new and useful Improvements in Saw-Frames; and I do hereby declare that the following is a full, clear, and exact description thereof, sufficient to enable others skilled in the art to which it appertains to make and use the same, reference being had to the accompanying drawings, and to the letters of reference marked thereon, and in which—

Figure 1 is a side view of my improved saw-frame, partly in section; and Fig. 2 is a similar view, showing the upper bar or spring and the lower bar as cut from the board previous to their disposition in the frame.

This invention relates to improvements in saw-frames, the purpose of which is to effect the ready and expeditious straining into position of the blade, the regulating of the pressure or tightening up of the parts, and the slackening up of the parts when it is desired to remove tension from the blade or for other purpose; and the nature of my invention consists in the employment, in a saw-frame, of two recurved bars with two points of contact between them, one near each of their ends, and united or bolted together at one of said points of contact, while a sliding ring or cuff is fitted to move thereon past their other point of contact, the upper bar being made sufficiently light to serve as a spring, substantially as hereinafter more fully set forth.

In the accompanying drawings, A A' mark the front and rear end pieces of the frame, with their upper ends connected together. It may be simply by passing cord *a* around them, as shown, without a tightening turn-buckle or nutted and screw-threaded rods, with ends looped over said end pieces, or without twisting the rope with an interposed stay resting at its free end against a middle bar, after the manner of a torsion-spring, as heretofore practiced.

B is the blade, with its ends connected, as is usual, by metallic pins or other suitable means, to and let into the lower end of the rear end piece, A', and into the front end piece, A, in the same horizontal plane with the said end of the rear end piece. Below this point

the front end piece forms the handle-extension for one hand to grasp, while the other hand catches or grasps the front end piece farther up in using the saw.

55

C' refer to two recurved bars, both of which are cut or partly formed at one operation from the same piece of board, as will be readily understood by reference to Fig. 2, one being cut of a less thickness than the other, as shown in the two figures, to serve as a spring when in use. These bars are disposed, the thicker one, C, so as to constitute a lower rigid bar of the frame, with its ends resting in mortises in the end pieces, A A', and its two or less convex surfaces *c c* presented upwardly, while the thin or light one, C', is disposed in a reversed position in the frame above the rigid bar C, with its coincident convexities *c' c'* presented to those of the bar C, thus producing two points of contact between the two bars or the spring and the brace, at one of which they are bolted or riveted or otherwise firmly united together, as at *d*, to secure the spring or pressure when acted on, as presently pointed out, at only one of their ends—the opposite end. The forward or one end of the spring C' fits into a mortise in the end piece, A, while its other fits into a slot, *e*, in the rear end piece, A', to permit it to have movement as it is acted upon or pressure removed therefrom.

D is a sliding ring or cuff fitted to be adjusted back and forth upon the rear ends of the brace and spring C C', between their oppositely-diverging surfaces, as fully illustrated in Fig. 1, the purpose of which, it is obvious, is to tighten or loosen the spring, as may be desired.

By sliding the ring or cuff D toward and causing it to compress the divergent end of the spring C' and press or hold the same down in the bottom of its slot in the end piece, A', or by moving it in a reverse direction, so as to act upon the recurved or convex surface of the spring C', as indicated in dotted lines in Fig. 1, the blade will be strained, and the straining pressure can be regulated as the ring is moved over a greater or less surface of the spring. This also tightens up the parts of the frame, while by moving the ring in the concavities formed by the curved upper and lower surfaces of the spring and brace C' the press-

ure will, to a degree, be taken off the spring, and the parts thus be loosened and the strain taken off the saw, as is desirable when not in use, the contrary being entirely unnecessary and holding the blade under tension.

This invention also permits the ready removal of the blade for its renewal or other purpose.

I claim and desire to secure by Letters Patent—

The combination, in a saw-frame, of the curved bar and spring C C', with one of their points of contact firmly united together, and provided with a ring or cuff, D, which is adapt-

ed to be moved past their other point of contact and apply pressure to said spring or be released from forcible contact therewith, with the end pieces, A A', with a slot, e, a saw-blade, and means for connecting the upper ends of the end pieces together, substantially as set forth.

In testimony whereof I hereto affix my signature in presence of two subscribing witnesses.

WM. H. HANKIN, JR.
